LICENSE PLATE HOLDER

Charles M. Harmer, Seattle, Wash.

Application August 10, 1948, Serial No. 148,041

Term of patent 7 years

(Cl. D14—6)

To all whom it may concern:

Be it known that I, Charles M. Harmer, a citizen of the United States, residing at Seattle, in the county of King and State of Washington, have invented a new, original, and ornamental Design for License Plate Holder, of which the following is a specification, reference being had to the accompanying drawing, forming part thereof.

Fig. 1 is a front elevation of a license plate holder showing my design.

Fig. 2 is a top edge view of the same.

Fig. 3 is a somewhat enlarged cross-sectional view of the device taken on line 3—3 in Fig. 1.

I claim:

The ornamental design for a license plate holder, as shown.

CHARLES M. HARMER,
